STAGE CONSTRUCTION

Anton F. Grot, Los Angeles, Calif.

Application July 22, 1940, Serial No. 346,788

20 Claims. (Cl. 272—10)

This invention relates to stage settings, and pertains particularly to a stage structure providing an effective simulation of the undulating surface of a natural body of water. My invention is particularly useful in producing a photographically effective simulation of water for cinematography.

One of the particular objects of the invention is to provide a stage structure carrying a plurality of relatively movable light-transmitting screen members arranged to establish a continuously shifting light and shadow pattern on a background drop to simulate the appearance of a body of water.

A further object of the invention is to provide a stage setting of the character above set forth, comprised of a plurality of separate structures disposed in contiguously aligned relationship, in which each structure is operated in a timed relation to the adjacent structures whereby the shifting light and shadow patterns provided by the respective structures are placed in consonance with one another and no demarcation of the separate light and shadow patterned areas of the adjacent structures is discernible.

A further object is to provide a structure of the character described, adapted for use in conjunction with a background drop, characterized by the provision of a supporting structure disposed rearwardly of such a drop and above a simulated horizon level, said structure carrying an operating head structure having a plurality of relatively movable light-transmitting screen members depending to positions below such simulated horizon level and including means for moving said screen members in a generally upward and downward direction in phase displaced relation, and means for directing light through said screen members upon the rearward surface of such background drop, said background drop being translucent at portions below such simulated horizon level.

Other objects and features of the invention will be brought out in the ensuing specific description of a particular embodiment thereof, as illustrated in the accompanying drawings, in which:

Fig. 1 is an end elevation of a device constructed according to the present invention, adapted to support and operate three separate light-transmitting screen members rearwardly of a background drop;

Fig. 1a is a fragmentary section of a portion thereof, as taken on line 1a—1a in Fig. 4;

Fig. 2 is a partly broken-away view thereof, taken on line 2—2 in Fig. 1;

Fig. 3 is an enlarged view of the screen support and drive mechanism, as taken on line 3—3 in Fig. 2;

Fig. 4 is a front elevation as taken on line 4—4 in Fig. 1, with the background drop and screens omitted;

Fig. 5 is a partly broken-away detail taken on line 5—5 in Fig. 3;

Fig. 6a is a front elevation of a type of light-transmitting screen member which may be employed for the simulation of a calmly undulating water surface;

Figs. 6b and 6c, respectively, are broken-away views of the upper central and lower central portions of screen members which may be used in superimposed relation to a screen member of the type shown in Fig. 6a;

Fig. 7a is a front elevation of another type of light-transmitting screen member which may be employed for the simulation of a stormy, turbulent water surface;

Figs. 7b and 7c, respectively, are broken-away views of the upper central and lower central portions of screen members which may be used in superimposed relation to a screen member of the type shown in Fig. 7a;

Fig. 8a is a front elevation of another type of light-transmitting screen member which may be employed for the simulation of a sweeping or moving body of water, such as useful as a background for a simulated ocean-going vessel;

Figs. 8b and 8c, respectively, are broken-away views of the upper central and lower central portions of screen members which may be used in superimposed relation to a screen member of the type shown in Fig. 8a.

Fig. 9 is a typical transverse section through a cinematographic stage setting utilizing the construction of the present invention; and

Fig. 10 is a plan view on reduced scale, showing the manner in which a plurality of separate cinematographic stage units of this invention may be arranged to simulate a large expanse of water surrounding a stage setting.

Referring to Figs. 1—5 of the drawings, the structure of the present invention may comprise a base portion 1 provided, if desired, with a plurality of supporting rollers 2 adapted to rest on a foundation or floor 3. Extending upwardly from the base 1 is a support structure 4 carrying a vertically adjustable operating head structure 5, and preferably also carrying a vertically adjustable platform member 6 which may be em-

ployed to carry lighting units or the like such as are illustrated more particularly in Fig. 9.

Mounted at the forward portion of the head 5 I provide a support structure 1 carrying a plurality of light-transmitting screen members 8a, 8b, and 8c, each of the screen members being mounted for vertical movement or reciprocation. The support structure 1 may comprise forwardly downwardly projecting support arms 9a, 9b, and 9c each carrying a roller member 11a, 11b, and 11c, respectively, at its forward end, said roller members being spaced from one another to provide clearance for the respective screen members.

The upper edges of the screen members 8a-8c are provided with a clamping strip as indicated at 12a, and 12b, and 12c, respectively, extending for substantially the full length of each such screen member, to which driving cables or the like 13a, 13b, and 13c are respectively attached, said driving cables being carried upwardly to operating rollers 14a, 14b, and 14c respectively, and secured thereto as at 15a, 15b and 15c. The rollers 14a-14c are rotatably mounted on the support 1 as at 16a, 16b and 16c, and are rotated in such manner as to cause the screens 8a-8c to reciprocate vertically in phase displaced relation.

This movement is readily obtained through the agency of a plurality of driving cables or wires connected to the respective rollers as at 17a, 17b, and 17c (seen best in Fig. 3), the cable 17a being carried rearwardly and over a pulley 18 and thence to a driving member 19 and is connected to a projection 21 carried thereby. The driving member comprises a collar rotatably secured upon a crank pin 22 mounted on one of the spokes of a driving wheel 23 which is rotatably mounted on a frame member 24 secured to the structure 5. The cable 17b is similarly connected to a projection 25 on the driving member 19, and the cable 17c is carried over a pulley 26 corresponding to the pulley 18 and thence to a third projection 27 on the driving member 19. The projections 21, 25, and 27 are conveniently spaced at equal angles from one another about the crank pin 22. The crank pin 22 may be caused to be positioned at any desired radial separation from the center of the driving wheel 23, as by threadedly mounting the same in any one of a plurality of holes 22a, 22b, etc., spaced progressively at increasing radial distances from such center. Placement of the pin in the different holes in the spokes of the driving wheel 23 will thus provide various lengths of stroke for the reciprocatory movement of the screen members 8a-8c.

The driving wheel 23 is driven at a reduced speed through the agency of a chain 31 operatively engaging a sprocket 32 mounted on a stub shaft 33 and secured to a larger sprocket 34 driven through a chain 35 by a sprocket pinion 36 mounted on a shaft 37. The shaft 37 extends for a part of the length of the frame 5 and is mounted for rotation with its ends projecting through spaced journals 38 and 39 secured to the frame 5. A sprocket 41 is provided on the shaft adjacent bearing 39 and is operatively connected through a drive chain 42 to a sprocket 43 which is driven through reducing gear carried by a motor 44.

It should now be apparent that operation of the motor 44 will cause rotation of the shaft 37 and the driving wheel 23. This results in a circular movement of the driving member 19 and since the driving cables 17a, 17b and 17c are guided to

this member, constituting a single throw crank, from different angular directions, rotation of this crank will result in an out of phase reciprocation of these cables. Since the cables are connected to the respective driving rolls 16a, 16b and 16c and the connecting cables 13a, 13b and 13c are also connected to these driving rolls the screen 8a, 8b and 8c will reciprocate with respect to the frame upon which the screens are mounted in 10 and out of phase relation to one another. Obviously other crank and connecting arrangements could be used in place of the one shown. For example, a conventional crankshaft arrangement, with three angularly displaced cranks, could be used.

However, the forces imposed on the structure are not very great and the system shown is advantageous because of its simplicity. In practice the screens are reciprocated at a relatively low rate, for example, at about five to 15 ten reciprocations per minute.

To prevent the screens from swinging at the bottom I provide a plurality of guide members 147 (Figs. 1 and 1a), each comprising a plurality of vertically extending partition members 148, 20 having their faces extending parallel to the faces of the screens and spaced from one another to provide slots in which the screens may reciprocate. Suitable means is preferably provided for biasing the screens downwardly to keep them 25 taut during reciprocation. Although numerous arrangements may be used, I conveniently provide rather heavy metallic stripping members 149, 149', 149'' attached to the bottoms of the respective screens as a load for this purpose, such stripping 30 corresponding generally to the strips 12a, 12b and 12c above.

It is to be emphasized that the structure as now described only constitutes a framework or frame means for mounting the screen members 35 and the driving means for reciprocating the same.

Although the particular framework described is particularly advantageous for this purpose and is part of my invention, it is to be understood that it is shown only by way of example and that other types of framework and driving mechanisms may be employed without departing from the broader aspects of my invention.

Each of the screen members 8a, 8b and 8c provides a plurality of relatively opaque areas interspersed with relatively transparent areas. A simple form of construction consists in fabricating the screen members from a transparent sheet of material such as Celluloid, "Cellophane" or the like and providing this member with relatively opaque areas. These opaque areas may be applied photographically or by painting or printing on the like.

Referring now to Figs. 6a, 7a and 8a, and the related Figs. 6b, 6c, 7b, 7c and 8b, 8c, the screen members each comprise a translucent and preferably transparent sheet 45 on which opaque markings are provided as at 46, 47 and 48 (Figs. 6a, 7a and 8a, respectively). These markings are so arranged as to provide a simulation of perspective from bottom to top, causing the resultant light and dark areas obtained by the superimposition of a plurality of screens to become smaller as the simulated horizon is approached. This is accomplished by using relatively coarse and widely spaced markings at the lower end of the screen, and relatively fine and closely spaced markings at the upper end of the screen.

The screens illustrated in Figs. 6a, 6b and 6c 70 may be used in the respective positions of screen

members 8a, 8b and 8c (Figs. 1 and 3) and the generally horizontal undulating markings of the type illustrated will, when reciprocated and illuminated as described, provide a simulation of the light and shadow appearance of a calmly undulating surface of a body of water. By experiment, it has been found that practically any arrangement of pattern or lines will be useful. The several superimposed screen members may carry similar opaque areas, such as shown in Fig. 6a, but somewhat more natural effects are produced by the use of differently marked superimposed screen members. For example, the markings 46 in Fig. 6a are extended as generally horizontal undulations, and the markings 46' in Fig. 6b and 46'' in Fig. 6c are arranged to provide a plurality of shallow "peaks."

Referring to Figs. 7a, 7b and 7c, I have shown three light-transmitting screen members which may be superimposed to create a simulation of a turbulent or stormy body of water the markings 47 being arranged in Fig. 7a as superimposed deep and shallow undulations, and in Figs. 7b and 7c the markings 47' and 47'' are arranged as similar markings in a different patterning.

In Figs. 8a, 8b and 8c, the markings 48, 48' and 48'' are arranged at an angle to the horizontal, but otherwise comparable to the markings 46, 46' and 46''. The effect produced by screen members of this type is that of a horizontally moving body of water, such as might be observed from a moving boat.

It will be noted that for each set of screen members a plurality of screen members is used. It is preferable to use at least three screen members and to reciprocate them in out of phase relation whereby a plurality of superimposed screen members are always in movement. However, for scenes which do not require the high degree of simulation required for most cinematography, such as some scenes on the legitimate stage, two screens reciprocating in out of phase relation will give satisfactory results.

In use, the present apparatus is employed for the production of simulative patterns by projecting light through the screens which are superimposed in the direction of light travel, from a position behind the screens. For example, a plurality of lights may be directed downwardly toward the screens from the platform 6 (see Figs. 1 and 9) and another plurality of lights may be directed upwardly toward the screens from a position adjacent the floor 3 and beneath the platform 6. Each of the opaque areas in the screens will of course intercept light from the light sources and prevent its passage through the screens to a position on the opposite side where the screens are to be used, viewed or photographed. Since the three screens are reciprocating in phase displaced relation the composite light and shadow pattern produced by the three screens will be constantly shifting and the resultant effect is the same as that produced by light striking and reflecting from the surface of a moving body of water.

Although the effect can be viewed from a position in front of the outer screen 8a, I prefer to project the light and shadow pattern onto a stationary transparent or translucent screen, drop, or backing member 50 of muslin, silk, or the like. This member in its upper extremities may be shaded, bleached, or painted, for example in the portion 51, to give the appearance of clouds and provides a horizon line 52. The screen or drop 50 is supported from above in any suitable man-

ner, as from the rafters of the studio or by means of other supports not shown. In order to prevent shadows of the machinery or framework from appearing on this screen I provide an opaque member such as a black cloth "goboe" or "black-out" 53 which is attached to the back of the member 50 at the horizon line 52 and extends upwardly over the operating mechanism and is suitably secured to a stationary member such as the top of the framework 4 by means of suitable cables 54. Even though the member 50 is stationary the effects of cloud movement and colors may be produced on the upper portions 51 thereof by means of shifting lights and colored lights, or by other means as desired.

Under some circumstances a single set of screens such as described above will have sufficient area to give the desired view. For example, a single set of screens may be used to simulate a body of water as viewed through a window or from a porch, or as a background for a scene including a rowboat or the like. For larger scenes such as ocean or beach scenes it is not practical to use a single large set of screens since the resulting structure would be too cumbersome to handle. For that reason I prefer to construct a large background by using a plurality of units as above described in side by side relation. Each of the units is preferably constructed so as to fit with a corresponding unit in such manner that the screens of the adjacent units overlap. Furthermore, I prefer to provide separate driving means for each unit to provide flexibility in rigging the scenes, but I prefer to rigidly connect the drive shafts of adjacent units so that the units will reciprocate in synchronism.

In Figs. 2, 4 and 5, it will be seen that the screens in a single unit (a single unit being illustrated in Figs. 4 and 5) have their vertical marginal portions on one side arranged in horizontally staggered relation as at 8a', 8b' and 8c' and their marginal portions on the other side staggered in a complementary manner. It will also be seen from an inspection of Figs. 2 and 5 that the connecting strips 12a, 12b and 12c are somewhat shorter, for example, one or two inches shorter than the screens to which they are connected. As a result the adjacent units as indicated at A and B in Fig. 2 may be placed in end to end relation with the corresponding connecting strips substantially abutting as at 12c' (Fig. 5) for example, and with the corresponding screens overlapping slightly as at 49 (Fig. 5). At the same time the staggered relation of the marginal portions of the screens tends to distribute the effect produced by joining the screens over a considerable area and does not give a sharply defined line of demarcation between the adjacent units which would be apt to be discovered.

Referring particularly to Fig. 2, it will be seen that the unit A is joined to a unit B on one side and to a third unit C on the other side. To provide for synchronizing the motions of these units an extension shaft 55 is provided to couple the shaft 31 to the shaft 37b on the unit C. The shaft 55 is preferably provided with splined sleeves 56 at each end which are adapted to encompass the shafts 31 and 37b and engage pins 57 projecting radially from these shafts. In order to accommodate any misalignment of the adjacent units the driving connection between the sleeves 56 and the pins 57 is preferably somewhat loose so as to give an action which is comparable to that provided by universal joints. A comparable extension shaft 55a pro-

vided with a splined sleeve 56a is furnished the unit B for coupling the drive mechanisms of the units A and B. The frame structures of the adjoined units A, B, and A, C, may be, and preferably are, rigidly connected together as at 58 and 59, through the agency of removable couplings or the like.

Referring now to Figs. 9 and 10, a typical stage set-up utilizing the construction of my invention is illustrated. Referring particularly to Fig. 10, a large scene is illustrated in which a water background is provided to substantially surround a pair of boats 61 and 62 which are suitably supported in a shallow tank 63 containing water. The background is provided by a plurality of units D which are arranged to substantially completely surround the tank. With the particular scene illustrated there are two units at the ends of the tank and four on each side. The corners are closed by curved translucent drops E which will not appear in the scene when the angle of view is correctly chosen but which tend to prevent extraneous light from reaching the interior of the scene. In Fig. 10 various positions for a camera or for viewing are indicated at 64, 65, 66, 67 and 68. The field of view in a horizontal plane for each of these positions is indicated by the dot-dash lines emanating therefrom. It will be seen that each of these positions can be so chosen as to include one or more of the units D for background without including the corners E.

In Fig. 9 a vertical section of part of the stage illustrated in Fig. 10 is shown and the unit D in this figure may be the same as the unit illustrated in Fig. 1. A light source 70 is provided on the platform 6 for illuminating the screens which are indicated in their entirety by the numeral 8 and a second light source 71 is shown located on the floor for directing light upwardly against the screens 8. These two lights will produce the shifting light and shadow pattern on the drop 50 upon reciprocation of the screen members as heretofore described.

The drop 50 is shown extending upwardly to provide a sky portion 51 which is illuminated by lights 72 and 73 which are supported by a suitable structure such as the walls of the studio or stage. These lights are used to illuminate the sky and/or produce the cloud patterns. The horizon line 52 on the drop 50, as well as the head structure 5 of the unit D may readily be adjusted vertically to bring the horizon into correct position as viewed from the decks of the boats. The actual location of the horizon line 52 does not necessarily conform to what would constitute "eye" level, inasmuch as exaggerated perspective effects may readily be obtained by disposing this horizon line above or below "eye" level.

As previously stated, the operating head structure 5 and the platform 6 are vertically adjustable on the support structure 4. The upwardly extending columns of the supporting structure are provided with a plurality of spaced openings 4a, and the head structure and platform are carried on tubular members 5a and 6a respectively which are slidable on the columns of the support structure 4 (see Fig. 1). The members 5a and 6a are locked in position on the columns by means of removable pins 5b and 6b which extend into the openings 4a. This construction gives great flexibility in that it allows vertical adjustment of the platform 6 and also of the operating head 5, whereby this head can be adjusted vertically to accommodate different height

screens and to provide for different horizon heights in different scenes.

In order to obviate the necessity of bringing the level of the water in the tank to the lower level of the shifting light and shadow pattern produced by my stage or of providing painted drops extending between these levels, the angles of view are usually chosen so as to prevent the line of demarcation between the edge of the water in the tank and this area to appear. For example, the scene may be viewed from positions 74 and 75 in which the hulls of the boats will effectively obscure this portion of the scene.

My invention is obviously subject to considerable modification, hence I do not choose to be limited to the above described examples but rather to the scope of the appended claims.

I claim:

1. A stage construction for producing shifting light and shadow patterns to simulate the appearance of a body of water, comprising: frame means; a plurality of screens movably mounted on said frame means and disposed in superimposed relation in the direction of light travel and each providing a plurality of relatively opaque areas interspersed with relatively transparent areas; and means for reciprocating said screens with respect to said frame means in phase displaced relation.

2. A stage construction for producing shifting light and shadow patterns to simulate the appearance of a body of water, comprising: frame means; a plurality of substantially vertically extending screens movably mounted on said frame means and disposed in superimposed relation in the direction of light travel and each providing a plurality of relatively opaque areas interspersed with relatively transparent areas; and means for reciprocating said screens vertically with respect to said frame means in phase displaced relation.

3. A construction as set forth in claim 2, the opaque areas and transparent areas of the respective screens generally progressively increasing in size from the top to the bottom of the superimposed portions of said screens.

4. A construction as set forth in claim 2, the opaque and transparent areas being generally elongated in a horizontal direction.

5. A construction as set forth in claim 2 and further comprising: a substantially vertically extending screen of diffusing light-transmitting material upon which the shadow pattern appears.

6. A construction as set forth in claim 2, there being at least three of said screens.

7. A stage construction for producing shifting light and shadow patterns simulative of the appearance of a body of water, comprising: frame means; a plurality of relatively movable light-transmitting screen members movably mounted on said frame means and disposed in a generally vertical relation and superimposed upon one another with respect to the direction of light transmission therethrough, each of said screen members being provided with a plurality of relatively opaque areas interspersed with relatively transparent areas; and means for moving said screen members with respect to said frame means transversely of said direction in phase-displaced relation to one another.

8. A construction as set forth in claim 7, said screen members being disposed in generally vertical parallel planes, and said means for moving said screen members being adapted to move said

screen members generally in an upward and downward direction in their respective planes.

9. A construction as set forth in claim 7, the relatively opaque and transparent areas of said screen members being generally progressively decreased in size from the lower portion thereof to the upper portion thereof.

10. A cinematographic stage construction for use in combination with a drop providing a simulated horizon line, for producing shifting light and shadow patterns simulative of a body of water defining such horizon line, which comprises: frame means; a plurality of relatively movable light-transmitting screen members movably mounted on said frame means and disposed in generally vertical planes rearwardly of such drop with respect to the position of the cinematographic camera means employed to produce the desired cinematographic register; illumination producing means positioned rearwardly of said screen members and adapted to direct light forwardly through said screen members upon the rearward surface of said drop; and means for moving said screen members in a generally up and down direction with respect to said frame means in phase-displaced relation.

11. A construction as set forth in claim 10, the relatively opaque and transparent areas of said screen members being progressively decreased in size and spacing upwardly toward the position of said horizon line.

12. The construction set forth in claim 10, and comprising in addition an opaque member secured to said drop at the position of said horizon line and positioned to shade the portion of said drop above said line from light produced by said illumination-producing means.

13. The construction set forth in claim 10, the relatively opaque and transparent areas of said screen members being progressively decreased in size and spacing upwardly toward the position of said horizon line, and said construction including an opaque member secured to said drop at the position of said horizon line and positioned to shade the portion of said drop above said line from light produced by said illumination-producing means.

14. The construction set forth in claim 10, said construction including a plurality of roller means carried by said frame means and extending in a generally horizontal direction and supporting the respective screen members in closely spaced relation to one another.

15. A construction as set forth in claim 10, in which said plurality of screen members comprises at least three screen members.

16. A stage construction for producing shifting light and shadow patterns to simulate the appearance of a body of water, comprising: vertically extending frame means; a plurality of horizontally extending laterally spaced rollers journaled for rotation on said frame means in the upper portions thereof; a screen for each of

said rollers, each of said screens providing a plurality of relatively opaque areas interspersed with relatively transparent areas, each of said screens extending substantially vertically downward from over one side of its roller; crank means journaled for rotation on said frame means; means for rotating said crank means; and means associating said crank means with each of said screens at positions on the other side of each of said rollers for moving said screens over said rollers in out of phase reciprocation.

17. A stage construction for producing shifting light and shadow patterns to simulate the appearance of a body of water, comprising: vertically extending frame means; a plurality of horizontally extending laterally spaced rollers journaled for rotation on said frame means in the upper portions thereof; a screen for each of said rollers, each of said screens providing a plurality of relatively opaque areas interspersed with relatively transparent areas, each of said screens extending substantially vertically downward from over one side of its roller; separate cable means connected to each of said screens at a position on the other side of its respective roller; a single throw crank journaled for rotation on said frame means; and means guiding said separate cable means to said single throw crank from different angular directions, whereby rotation of said crank produces out of phase reciprocation of said screens.

18. A stage construction for producing shifting light and shadow patterns to simulate the appearance of a body of water, which comprises: a plurality of interchangeable units arranged in side-by-side relation, each of said units comprising: frame means; a plurality of substantially vertically extending screens movably mounted on said frame means and disposed in superimposed relation in the direction of light travel and each providing a plurality of relatively opaque areas interspersed with relatively transparent areas; and means for reciprocating said screens vertically with respect to said frame means in phase displaced relation, the screens in each unit having their vertical marginal portions on one side arranged in horizontally staggered relation and their marginal portions on the other side staggered in a complementary manner, whereby said units may be placed side by side, with corresponding screens in adjacent units substantially abutting and with the vertical marginal areas of screens in adjacent units superimposed in the direction of light travel.

19. A construction as set forth in claim 18, further comprising means for synchronizing the motion of corresponding screens in adjacent units.

20. A construction as set forth in claim 18, each of said units comprising three of said substantially vertically extending screens.

ANTON F. GROT.
